UNITED STATES PATENT OFFICE.

WILLIAM F. TALBERT, OF FUNKSTOWN, MARYLAND.

CORN-PLANTER.

SPECIFICATION forming part of Letters Patent No. 707,733, dated August 26, 1902.

Application filed June 18, 1902. Serial No. 112,233. (No model.)

To all whom it may concern:

Be it known that I, WILLIAM F. TALBERT, a citizen of the United States, residing at Funkstown, in the county of Washington and State 5 of Maryland, have invented a new and useful Corn-Planter, of which the following is a specification.

This invention relates to corn-planters; and it has for its object to provide a machine of 10 this class which shall possess superior advantages, whereby it shall be enabled to perform work in an easy and satisfactory manner.

My invention has for its special object to provide a machine the frame parts of which 15 shall be adjustable laterally, so that the seed-ing mechanisms carried by said frame may be spaced at different distances apart, thus vary-ing the distance between the rows. This and other objects which will presently appear are 20 accomplished by the construction, arrange-ment, and relative disposition of the compo-nent parts of the device, which will be herein-after fully described, and particularly point-ed out in the claims.

25 In the accompanying drawings, Figure 1 is a plan view of a corn-planter constructed in accordance with my invention. Fig. 2 is a longitudinal vertical sectional view of the same. Fig. 3 is a detail plan view of a portion of the 30 front end of the lower frame of the machine, showing the front end of one of the plow-beams connected therewith.

Corresponding parts in the several figures are indicated by like characters of reference.

35 My improved corn-planter is provided with two separate frames, the upper frame 1 being supported upon the axle 2, which is mounted revolvably in boxes or journals 3 upon the under side of said frame. The traction-wheels 40 4 may be fixed upon the ends of the axle; but I prefer that one of them shall be mounted revolvably thereon for convenience in turning.

The upper frame 1 is composed of side 45 pieces 5, upon the under sides of which the boxes 3 are suitably secured. The rear ends of said side pieces 5 are bent inwardly toward each other, as shown at 6, and are pro-vided with overlapping ends 7, shouldered, 50 at shown at 8, so that when the side pieces are brought closely together the said over-lapping ends shall abut against the shoul-

ders of the opposite side pieces. Connecting-bolts 9 are provided, and the overlapping ends are provided with series of perforations 55 for the reception of said bolts to permit con-nection to be made at various points of ad-justment. The side pieces 5 are provided on their inner sides near their front ends with brackets 11, extending inwardly toward each 60 other and overlapping each other, and connecting-bolts are provided whereby the said overlapping ends may be secured at various points of adjustment, each end being pro-vided with a series of transverse perforations 65 for the reception of said bolts.

The front ends of the side pieces 5 of the upper frame are bent or curved downwardly and inwardly, as shown at 14, and said de-pending ends are transversely perforated for 70 the reception of a connecting-bar 15, which pivotally supports what may be termed the "lower" frame of the machine. Said lower frame comprises, especially, the beams 16 of the plows or furrow-openers, the front ends 75 of which are bifurcated, as shown at 17, and transversely perforated for the reception of the connecting-rod 15.

18 designates a yoke, the ends of which are transversely perforated also for the reception 80 of the connecting-rod 15, the said perforated ends of the yoke engaging the bifurcated front ends of the beams 16, thus effecting a very secure and at the same time a suffi-ciently flexible connection of the parts. It 85 will be seen that the ends of the yoke engaging the bifurcated ends of the plow-beams pre-vent the latter from spreading outward, while the downturned front ends of the side pieces of the upper frame bear against the inner 90 sides of the bifurcated ends of the plow-beams, thereby spacing them apart.

The yoke 18 is composed of two separate parts or members 18^a 18^b, overlapping each other and connected adjustably by means of 95 bolts 18^b, for the reception of which series of perforations 18^a are provided.

The tongue 19 of the machine rests upon the upper frame 1 and is provided with clips 20, embracing the overlapping parts at the 100 front and rear ends of said frame, with which it is thereby connected. Sufficient rigidity of connection may be attained by tightening the nuts 21 upon the clips 20, and the latter

thus serve not only to support the tongue upon the frame, but also to assist in connecting the parts of the latter together. A coupling pin or bolt 22 extends vertically through the tongue and through the central portion of the yoke 18. This provides an additional connection between the upper and lower frames and serves likewise for the attachment of a central bracket 23, corresponding with the ends of the yoke 18 and having a transverse perforation for the accommodation of the connecting-rod 15. To this bracket, which has been illustrated in Fig. 3 of the drawings, the bifurcated front end of one of the plow-beams 16 may be connected. This may sometimes be desired, as when it is desired to use three plows or if only a single centrally-disposed one is required.

The right-hand side of the upper frame supports a rack-segment 24, which forms one of the bearings for a transverse shaft 25, the opposite end of which is journaled in a box 28 at the opposite side of the frame. The shaft 25 is composed of two separate members 25^a and 25^b, the latter of which has a socket 27, in which the squared end of the shaft member 25^a is slidingly mounted. It will thus be seen that these shaft members revolve in unison, thus practically constituting a single shaft, while the sliding connection between them enables the sides of the frame to be adjusted laterally with relation to each other without interfering with the operation of this part of the device.

35. The ends of the shaft members are provided with cranks 30, having pivotal connection with the upper ends of pitmen 31, the lower ends of which are extended through the brackets 32, extending laterally from the plow-beams 16. The pitmen 31 have shoulders 33 near their upper ends to support the upper ends of springs 34, which are coiled upon the said pitmen and the lower ends of which bear against the brackets 32, thereby tending to force the plow-beams in a downward direction. These springs permit the plow-beams to have an upwardly-yielding movement, permitting them to ride over obstructions which might otherwise tend to injure parts of the machine.

50. The shaft member 25^a carries a lever 34, having a dog 35, operated by a handle 36 and engaging the teeth of the rack 24 and operating to maintain the lever and shaft at any desired adjustment. By this means the shaft may be tilted in its bearings, thus throwing the cranks to elevate or depress the plow-beams and the parts supported thereon, as may be desired. The plow-beams 14 support 55 near their front ends boxes or bearings 37, in which a transverse shaft 38 is revolubly mounted. Near their rear ends the said plow-beams support the seedboxes or hoppers 39, the sides of which afford bearings for a shaft 60. The rear ends of the plow-beams also carry the standards 41, supporting the furrow-openers 42 and covering devices 43. All

these parts, as well as the seeding mechanism, may be of any suitable approved construction, and as regards the seeding mechanism, which 70 is no part of the present invention, no attempt has been made to illustrate it in the accompanying drawings.

The axle of the machine is provided with a clutch consisting of a fixed member 44 and a 75 sliding member 45, which latter may be operated by a lever 46, disposed in a position convenient to the driver, to throw it into or out of engagement with the fixed clutch member 44. Normally, it is held in such engagement by the action of a spring 47, coiled upon the axle between the outer end of said sliding clutch member and a collar 48, fixed thereon. A notched beveled-edged projection 49 extends laterally from the tongue, as 80 shown in Fig. 1. With it the lever 46 may be placed in engagement when it shall be desired to retain the sliding clutch member 45 out of engagement with the fixed clutch member 44 against the tension of the spring 47. 90

The sliding clutch member 45 carries a series of differently-sized sprocket-wheels 49^a, any one of which may be connected by a chain 50 with a sprocket-wheel 51 upon the shaft 38. The sprocket-wheel 51 has a hub 95 52, provided with a set-screw 53, whereby it may be secured in any desired position upon the shaft, thereby enabling it to be placed in alignment with any one of the sprockets 49^a. By removing or adding links from or to the chain 50 the latter may be fitted to connect the sprocket 51 with any one of the sprockets 49^a. Provision is thus made for regulating the speed of parts operating from the axle of the machine.

105. The shaft 38 is provided with additional sprocket-wheels 54, connected by chains 55 with sprocket-wheels 56 upon the shaft 40, which has its bearings in the seedboxes and which serves to actuate the seed-dropping mechanism of the machine. The shaft 40 is composed of three separate joints or members 40^a 40^b 40^c, the central one, 40^a, being connected with the end sections by means of sleeves 57, which permit the said three sections to revolve independently. By this means when it shall be desired to use only one side of the planter one of the chains 55 may be removed, and thus motion will be transmitted only to the planting mechanism 110 120 at one side of the machine. It is obvious that the sprocket-wheels 56 are to be mounted upon the end sections 40^b of the shaft 40. I desire to state with relation to this that, while it is preferred that the chains 55 and the 125 sprockets for transmitting motion to the shaft 40 should be arranged between the hoppers of the machine, this is unimportant, as they may be equally well arranged adjacent to the outer sides of said hoppers, as shown in dotted lines in Fig. 1.

130. As will be readily understood, the axle of the machine, as well as the shafts 15, 38, and 40, should be made of sufficient length to en-

able the sides of the frame to be separated to the widest point of adjustment without interfering with the usefulness of said shafts. They have been so shown in the drawings.

5 In like manner the construction of the shaft 25 of two sections having sliding engagement with each other provides for the extension of said shaft to any length that may be required at any point of adjustment of the 10 side members of the frame of the machine.

A spring 60 is preferably coiled upon the bolt 22 between the tongue 19 and the yoke 18 or the bracket 23, extending rearwardly from the latter, for the purpose of spacing 15 the said yoke and tongue apart.

An ordinary spring-seat 61 is mounted in the usual manner upon the tongue of the machine in a position which will enable the driver to have convenient control of the 20 levers 34 and 46.

Having thus described my invention, I claim and desire to secure by Letters Patent of the United States—

1. In a machine of the class described, the 25 upper frame composed of side members having inwardly-bent and overlapping rear ends, downwardly and inwardly curved front ends, brackets secured to the inner sides of said side members and having inwardly-bent overlapping 30 ends and suitable connecting means, substantially as set forth.

2. In a machine of the class described, the upper frame composed of side members having overlapping rear ends, brackets secured 35 to said side members and having overlapping ends, the tongue supported upon the overlapping parts of the frame, and clips embracing the latter and connecting them to the tongue, substantially as set forth.

40 3. In a machine of the class described, the upper frame composed of separable side members, laterally adjustable with relation to each other, the tongue supported upon said frame, clips engaging the overlapping members of the latter and connecting them with the tongue and a lower frame having pivotal connection with the downwardly and inwardly curved side members of the upper frame by a transverse connecting-rod, substantially as 50 set forth.

4. In a machine of the class described, the upper frame having side members laterally adjustable with relation to each other and provided with downwardly-curved front ends, a 55 transverse connecting-rod extending through said ends, plow-beams having bifurcated, transversely-perforated front ends engaging said connecting-rod, and a yoke composed of separable and adjustable members, transversely 60 perforated at their ends and engaging the transverse connecting-rod and the bifurcated front ends of the plow-beams, substantially as set forth.

5. In a machine of the class described, the 65 combination of an upper frame composed of separable and relatively adjustable side members, a tongue supported upon said frame and

having clips embracing the overlapping members thereof, a transverse connecting-rod extending through perforations at the front 70 ends of the downwardly-curved side members of the upper frame, the plow-beams having bifurcated and transversely-perforated front ends pivotally engaging said connecting-rod, a yoke composed of separable, relatively 75 adjustable members having transversely-perforated ends engaging the connecting-rod and the bifurcated front ends of the plow-beams, a connecting rod or bolt forming a vertical connection between the 80 yoke and the tongue of the machine, and a bracket mounted upon said bolt and having a transverse perforation engaging the transverse connecting-rod, substantially as set forth. 85

6. In a machine of the class described, the combination of an upper frame composed of separable and relatively adjustable side members, a tongue supported upon said frame and having clips embracing the overlapping members thereof, a transverse connecting-rod extending through perforations at the front 90 ends of the downwardly-curved side members of the upper frame, the plow-beams having bifurcated and transversely-perforated front 95 ends pivotally engaging said connecting-rod, a yoke composed of separable relatively adjustable members having transversely-perforated ends engaging the connecting-rod and the bifurcated front ends of the plow-beams, 100 a vertical bolt forming a connection between the yoke and the tongue of the machine, and a spring coiled upon said bolt to space said tongue and yoke apart, substantially as set forth. 105

7. In a machine of the class described, the combination of a frame composed of separable and relatively adjustable side members, connecting means for the overlapping ends of said side members, an axle journaled in 110 boxes attached to the side members of said frame and having supporting-wheels thereon, plow-beams having pivotal connection with the depending front ends of the side members of said frame, seeding mechanism supported 115 at the rear ends of said plow-beams, a transverse shaft journaled in boxes near the front ends of the plow-beams, and means for transmitting motion between said shaft and the axle and between said shaft and the seeding 120 mechanism, substantially as set forth.

8. In a machine of the class described, the upper frame composed of relatively adjustable side members having overlapping parts, a tongue supported upon said overlapping 125 parts and having clips embracing the same, plow-beams having pivotal connection with said upper frame, a yoke composed of separable, relatively adjustable members connecting the front ends of said plow-beams, a shaft 130 supported upon the side members of the upper frame and composed of two members slidably connected, cranks at the ends of said shaft, suitable connections between said

cranks and the plow-beams, and means for operating the crank-shaft, substantially as set forth.

9. In a machine of the class described, the combination of an upper frame composed of separable relatively adjustable side members, a wheeled axle supporting said frame, plow-beams having pivotal connection with said frame, a transverse shaft supported in 10 bearings upon the plow-beams near their front ends, seed-hoppers supported upon said plow-beams near their rear ends, a transverse shaft journaled in said hoppers, said shaft being composed of three members connected 15 at their meeting ends by couplings which permit them to revolve independently of each other, means for transmitting motion between

the end sections of said shaft and the transverse shaft supported at the front ends of the plow-beams, means for transmitting motion 20 between the latter shaft and a clutch-sleeve mounted slidably upon the axle of the machine, and means for operating said clutch-sleeve to throw the latter into or out of engagement with a fixed clutch member upon 25 the axle, substantially as set forth.

In testimony that I claim the foregoing as my own I have hereto affixed my signature in the presence of two witnesses.

WILLIAM F. TALBERT.
